AUTOMATIC CLOTH-SPREADING MACHINE
Frederick Kibler, Whitestone, N.Y., and Harold Z. Shapiro, East Orange, N.J., assignors to Spreading Machine Exchange, Inc., New York, N.Y., a corporation of New York

Filed Sept. 20, 1960, Ser. No. 57,314
7 Claims. (Cl. 270—31)

This invention relates generally to machines for spreading and folding cloth in superposed layers on a table for cutting the layers simultaneously into garment pieces, and more particularly to a novel mechanism for reversing the spreader box of such a machine as each layer is completed.

In the garment industry it is customary to mass produce the pattern-pieces necessary for a run of a given model and size of garment by simultaneously cutting such pieces from numerous superposed layers of cloth each of which comprises the material of at least one individual garment. The cloth is obtained in compact condition, usually rolled in a cylinder or sometimes folded in flat form, and it is then necessary to spread it in elongated superposed layers for the cutting operation. This is done by spreading layers of the cloth longitudinally along a cutting table to the appropriate length, usually of the order of at least several yards, and then folding the cloth back over each such layer in a continually reversing sinuous pattern to spread succeeding layers of the same length thereover, repeating the process until the required number of layers has been accumulated.

In modern times, the well-known automatic cloth-spreading machine has been developed to perform the function of arranging the material on the cutting table in this manner. Such machines typically have a carriage which holds a supply of cloth and reciprocates longitudinally of the cutting table, and a spreading box mounted on the carriage which engages the cloth and spreads it in layers along the table as the carriage reciprocates. The spreader box has a pair of bight-forming blades on one end and cloth-spreading means on the opposite end. Therefore, the box, which faces in one direction as the carriage traverses through one spreading stroke, must be turned about at the end of that stroke to move the blades into position to make a bight which forms the fold at the end of the current layer, and also to face the opposite way for spreading the next layer during the succeeding oppositely directed traverse of the reciprocating carriage.

Accordingly, there must be a reversing mechanism which turns the spreader box about in response to the arrival of the carriage at each of the opposite limits of its reciprocatory movement. The problems of designing such a mechanism are complicated by the fact that as the pile of superposed cloth layers increases in height the spreader box must be progressively elevated to be able to spread each succeeding layer atop the previous ones. As a result, the reversing mechanism must be arranged to make some sort of self-adjusting driving connection to the spreader box in order to drive the latter through its periodic reversing motion at any of the various different vertical positions which it assumes during the course of the spreading operation.

The problem has been solved to some extent by providing a rotary drive journaled at a fixed location on the reciprocating carriage, and an arrangement of stationary stops fixed to the cutting table and a cam track cooperating therewith to engage the rotary drive as the latter moves with the carriage so as to turn the rotary drive over at the limits of the reciprocatory movement. Then a self-adjusting coupling is provided to connect

2

the fixed rotary drive to the moving spreader box. In the past this coupling has been in the form of a chain drive trained over a quartet of sprockets mounted at the corners of a pantograph linkage. Such complex coupling has never been completely satisfactory, however, chiefly because in practice it has turned out to be overly delicate and sensitive to slight misalignments and therefore difficult to assemble and maintain.

Accordingly, it is an object of this invention generally to provide, for connecting a stationary rotary drive to a moving mechanism such as a spreader box, a self-adjusting coupling which will avoid the disadvantages of previous expedients. In particular it is an object of the invention to provide a coupling of this type which will be relatively simple, sturdy, and flexible enough in operation to compensate for small inaccuracies in the construction and assembly thereof.

In accordance with this invention, there is provided a mechanism for turning the spreader box of a cloth-spreading machine in each of its various vertical positions, the mechanism comprising a driving crank rotatably mounted at a fixed location on the carriage of the cloth-spreading machine, means for turning the driving crank over as the carriage reaches the limits of its reciprocation, a driven crank operatively connected to turn the cloth-spreader and to move vertically therewith, lever means, means making a rotary driving connection between the lever means and each of the cranks and permitting sliding motion of the lever means between the cranks to compensate for vertical movement of the driven crank, and means providing a floating pivot mounting the lever means for pivotal movement whereby to transmit turning motion between the cranks and for floating movement in response to vertical movement of the driven crank.

The foregoing brief summary, as well as further features and advantages of the invention, may best be appreciated by reference to the following detailed description of an illustrative embodiment, when read in conjunction with the accompanying drawings, wherein:

FIG. 1 is a side elevational view of an automatic cloth-spreading machine incorporating a spreader-box reversing coupling in accordance with the present invention;

FIG. 2 is an enlarged side elevational view of the reversing coupling of FIG. 1 in a lowered operating position;

FIG. 3 is a side elevational view similar to FIG. 2, but illustrating the coupling in the position assumed after having been moved to turn over the spreader box, and with parts thereof illustrated in phantom in an elevated operating position to demonstrate the manner in which the coupling adjust for vertical movement of the spreader box;

FIG. 4 is a vertical section taken along the line 4—4 of FIG. 2;

FIG. 5 is a horizontal section taken along the line 5—5 of FIG. 2;

FIGS. 6A, 6B and 6C are schematic representations of the spreader box laying down a plurality of layers of textiles; and

FIG. 7 is a schematic and exploded view of the linkage arrangement which functions to sommersault the spreader box at the end of each transverse movement of the device.

Before referring to the details of the present invention, reference is made to FIGS. 6A, 6B and 6C. In FIG. 6A it is seen that a clamp 62 is effective to hold a layer of cloth 22 on the table 10. A spreader box, generally designated by the numeral 28, and being generally of U-shaped configuration (see FIG. 4), including a first leg 58, a

second leg 60 and a cross member connected to the shaft 30, is shown moving toward the right to lay a single ply of fabric 22 on the table 10. In FIG. 6B, the spreader box 28 is shown in phantom as it is sommersaulted through a counterclockwise rotation of 180°. The solid line configuration illustrates the spreader box 28 after the sommersaulting. As may be seen, the lower front edge of the blade 58 forms a fold F in the fabric 22 which will be clamped to the table 10 by the clamp 62, after the spreader box 28 is moved to its extreme right hand position and then again toward the left. In FIG. 6C, the spreader box 28 is shown in phantom during its clockwise rotation and, in solid line, immediately after it has completed the clockwise sommersault of 180°. The edge of the blade 60 is effective, at the completion of this motion, to form a second fold F' which will be clamped to the table by the left hand clamp 62. The process is continuously repeated.

Referring in detail to the drawings, FIG. 1 illustrates an automatic cloth-spreading machine of a general type that is well known in the art. The machine is mounted atop a cutting table 10 and includes a pair of cloth-holding assemblies 12 immovably attached in spaced, confronting relationship upon the table 10, and a carriage 14 which is reciprocable longitudinally of the table 10 between the cloth-holding assemblies. The carriage 14 approaches each of the cloth-holding assemblies 12 alternately, trailing a layer of cloth along the table 10 as it proceeds, and forming an end fold as it approaches each of the cloth-holding assemblies. The latter then grip and clamp down the end fold, while the carriage 14 traverses in the opposite direction to spread the folded-back layer of cloth over the preceding layer and repeat and the process.

The carriage 14 includes a frame 16 carrying wheels 18 upon which it travels along the table top, and a platform 20 for holding a supply of cloth 22 folded into flat form. The cloth is fed from the platform 20 upwardly over a pair of roller guides 24 and 26 journaled on frame 16 and then downwardly to the spreader box 28, seen in FIG. 5. The latter is fixed to a shaft 30 which extends through, and is journaled on, a block 32 supported for vertical movement on the frame 16 by means of a drive chain 34 to which the block 32 is clamped. The top and bottom of drive chain 34 are trained over sprockets 36 journaled on the frame 16. One of these sprockets is rotated in the usual manner through a small predetermined arc by an adjustable pawl drive (not shown). The latter is actuated repeatedly by successive contacts with a cloth-holder assembly 12 as successive layers of cloth are accumulated so as to index the assembly of the block 32, shaft 30, and spreader box 28 upwardly in small steps as the succeeding layers of cloth repeatedly increase the height of the pile. An alternative supply of cloth may be provided by a cylindrical roll 38 rotatably mounted in a cradle 16a formed on the frame 16, the cloth being unreeled from the roll 38 directly down to the spreader box 28.

The spreader box shaft 30 is rotated for turning over the spreader box 28 by a coupling 40 in accordance with this invention, the coupling being driven by a shaft 42, as will hereinafter be more fully explained. The drive shaft 42, as seen in FIG. 5, is journaled at a fixed location on the frame 16. Fixed to the inner end of the drive shaft 42 for turning thereof is a crank arm 44 which in turn is driven by a cam follower pin 46 secured thereto at a radial distance from drive shaft 42. Pin 46 rides in a track 48 formed in a cam plate 50 mounted on a horizontal carrier rod 52. A washer 47, seen in FIG. 5, separates the crank arm 44 from the plate 50. The carrier rod 52 is mounted on the frame 16 for horizontal sliding movement relative thereto in the direction of reciprocation of carriage 14. Normally the assembly of the carrier rod 52 and cam plate 50 bearing track 48 is carried along with the carriage 14 as it reciprocates, but just before the carriage reaches the cloth-holders 12 at the limits of its travel, stops 54 and 56 on the cloth holders engage and restrain the carrier rod 52. As a result, in finishing its motion the

carriage 14 moves a sufficient distance relative to the carrier rod 52 and cam plate 50 to make the cam follower pin 46 which travels with carriage traverse the track 48 in alternate directions as the carriage comes to the limits of the respective alternating traverses of its reciprocatory motion. The cam track 48 is formed with a peak 48a shaped to sweep the pin 46 upwardly and then downwardly again in two successive quarter-circular arcs as the pin traverses the cam track in either direction. The ongoing motion of drive shaft 42 as it is carried along with the carriage 14 causes the crank arm 44 to swing over center as peak 48a is passed so that the pin 46 performs the two successive quarter-circular arcs in the same angular direction for any one traverse of the cam track 48. The result is a periodic cycle of half turns performed by the drive shaft 42 in alternating angular directions as the carriage comes to the limits of respective alternating traverses. Consequently the spreader box 28 performs oppositely directed half sommersaults at the ends of the respective oppositely directed traverses of the carriage 14.

This movement turns the spreader box 28 about at the end of each cloth-spreading pass to face the opposite way for the return cloth-spreading pass. In addition, it serves to swing bight-forming blades 58 and 60, seen in FIG. 4, downwardly and forwardly against the cloth to form a protruding bight therein, the respective blades 58 and 60 operating at the limits of respective oppositely directed carriage traverses. The bight so formed is then clamped downwardly by the adjacent cloth-holder assembly 12, leaving an end fold in the cloth as the carriage moves off again in the other direction.

The cloth is held down by clamping feet 62 carried at one end of a pair of arms 64 and 66, the other ends of which are pivotally mounted so as to allow raising of the clamping feet to insert the end folds therebelow and also to keep the clamping feet atop the growing pile of cloth layers. The pivotal mountings for arms 64 and 66 are designed to keep the lower or clamping surface of the feet 62 horizontal as the arms are pivoted. A connecting member 68 is pivotally connected to the ends of arms 64 and 66 at different locations so as to provide slightly different arcuate paths through which the arms pivot. The connecting member 68 is slidably mounted on a base member 70 but is prevented from rotating thereon by a pair of pins projecting from the connecting member 68 and engaging a horizontal slot 70a at the rear of the base member. The sliding motion of the assembly along the horizontal slot 70a is controlled by an arcuate vertical slot 70b at the front base member 70 through which passes a pin projecting from the arm 64.

Camming arms 80, one of which is seen in FIG. 1, extend from the carriage 14 and slope downwardly toward the cloth-holding assemblies 12. The camming arms 80 engage and cam the arms 64 upwardly to raise the clamping feet 62 as the carriage 14 approaches each of the cloth-holding assemblies 12. Then the folding blades 58 and 60, as they protrude the cloth to form a bight therein, push the bight under the raised clamping feet 62. When the carriage 14 subsequently withdraws to make its return traverse, the camming arms 80 are thereby retracted, lowering the clamping feet 62 to the top of the pile of cloth layers to compress and secure the bights in place and thus form the end folds of the cloth layers.

In accordance with this invention, the coupling 40 which transmits the periodic back-and-forth half turns of the stationary drive shaft 42 to the vertically movable spreader box shaft 30 includes a driving crank 90 fixed to the drive shaft, a driven crank 92 fixed to the spreader box shaft and movable vertically therewith, a lever assembly 94 making a rotary driving connection between the cranks, and a pantograph linkage 96 mounting the lever assembly both for pivotal movement to transmit turning motion from the driving crank to the driven crank and for floating movement to adjust the lever assembly for different vertical positions of the driven crank. The in-

terrelationships of the cam tract 48, the driving crank 90, the driven crank 92, the lever assembly 94, and the spreader box 28, with its associated shaft 30, may be conveniently seen in the exploded view of FIG. 7. It may be often convenient, during the course of the following description, to refer to FIG. 7 for a simplified illustration of the various members of the assemblies even though that figure illustrates some of the individual parts in somewhat distorted configuration.

As best seen in FIGS. 2 and 5, the cranks 90 and 92 include respective identical first crank arms 98 and 100 fixed at one end thereof to ends of the respective shafts 42 and 30 which protrude outwardly from the carriage 14. The crank arms 98 and 100 may be in the form of short, heavy gauge rectangular steel bars formed with appropriate bores to receive the ends of the shafts 42 and 30 respectively and transverse bores receiving keying pins or set screws to lock the crank arms to the shafts for rotation therewith. This construction is sturdy and makes for ready assembly and disassembly. First connecting pins 102 and 104 project outwardly from crank arms 98 and 100 and are spaced from the respective shafts 42 and 30 so as to rotate at a radial distance therefrom and thereby make a rotary driving connection to the lever assembly 94. The pins 102 and 104 are short, thick, steel dowels which may be received in bores formed in the respective crank arms 98 and 100 and also locked in place by set screws or keying pins.

The lever assembly 94 includes a first lever 106 in the form of a sturdy steel bar formed with longitudinally elongated slots 106a and 106b at opposite ends thereof which receive the first connecting pins 102 and 104 respectively to make a rotary driving connection to the crank arms 98 and 100. The widths of slots 106a and 106b are selected in relation to the diameters of the respective connecting pins 102 and 104 to fit closely thereabout so that rotary motion is transmitted between the crank arms 98, 100 and the lever 106 without a great deal of backlash, yet loosely enough for the connecting pins to be freely slidable along the length of the slots to allow longitudinal motion of the lever without disrupting the rotary driving connection. For reasons which will subsequently be explained, the lever assembly 94 also includes a second lever 107 identical to the first lever 106 and formed with slots 107a and 107b identical to the slots 106a and 106b.

In order to make rotary driving connections between the cranks 90, 92 and the second lever 107, the first connecting pins 102 and 104 are made long enough to project entirely through the respective slots 106a and 106b, and second crank arms 108 and 109, identical to the first crank arms 98 and 100, are fixed at one end to the outwardly projecting ends of the pins 102 and 104 in the same manner that the pins are fixed to the first crank arms 98 and 100. Second connecting pins 110 and 111, identical to the first connecting pins 102 and 104, are similarly fixed to the other ends of the second crank arms 108 and 109 respectively at a radial distance from the respective shafts 42 and 30, and project outwardly from these crank arms to make the same sort of longitudinally slidable rotary driving engagement with slots 107a and 107b respectively that the first connecting pins 102 and 104 make with the slots 106a and 106b respectively.

The pantograph linkage 96 may be any four bar linkage connected between the cranks 90 and 92 in a manner to support the lever assembly 94 for motion about a pivot substantially midway between the cranks, thus assuring that the arms of the lever assembly 94 connected to the respective cranks 90 and 92 will be approximately equal. The linkage 96 includes four bars 112, 113, 114, and 115 pivotally connected to form a diamond-like arrangement by means of pivot pins 116, 118, 120 and 122 located at the corners of the diamond. The bars 112, and 113 have integral extensions 112a and 113a respectively extending downwardly to make pivotal connections

to the drive shaft 42 and the spreader box shaft 30 respectively to mount the diamond linkage therebetween.

The lowermost pivot pin 120 of the diamond linkage extends pivotally through the levers 106 and 107 midway between the elongated slots at their opposite ends, thus mounting the levers for rotation about the pivot pin in response to the driving of crank 90. The spatial arrangement which permits the diamond linkage 112-115 and the cranks 90, 92 to be connected to levers 106 and 107 in this manner is best seen in FIG. 5. One of the upper diamond linkage bars 112 occupies a plane nearest the frame 16, and is spaced therefrom by a washer 124 surrounding the shaft 42. The other upper diamond linkage bar 113 is located in the next plane outwardly therefrom, and is spaced from the frame 16 by a washer 126 surrounding shaft 30 which has an axial thickness approximately equal to the axial thickness of washer 124 plus the thickness of bar 112 in order to properly position the bar 113. The next plane outwardly of bar 113 is occupied by the first crank arms 98 and 100, these being of equal thickness. A washer 128 having a thickness approximately equal to that of the bar 113 is located in the plane of that bar surrounding shaft 42 to properly position crank arm 98 in the plane of crank arm 100. The next plane outwardly thereof is occupied by the first lever 106, the succeeding plane by the second crank arms 108 and 109 which are also of equal thickness, and the plane after that by the second lever 107. The lower diamond linkage bars 114 and 115 are interspersed with the levers 106 and 107, the bar 115 being in the plane between the upper diamond linkage bar 112 and first lever 106, and the bar 114 being in the plane between the first and second levers 106 and 107. A washer 130 having an axial thickness equal to the thickness of one of the first crank arms 98 or 100 plus the thickness of the first lever 106 surrounds the pivot pin 118 to properly position the bar 114.

The lengths of the upper diamond linkage bars 112 and 113 between pivot pins 116-122 and 116-118 respectively are equal, as are the lengths of the lower diamond linkage bars 113 and 114 between pivot pins 122-120 and 118-120, and the lengths of the lower extensions 112a and 113a between pivot pin 122 and shaft 42 and between pivot pin 118 and shaft 30, these lengths being so chosen that the lower pivot pin 120 is located along the line between shafts 42 and 30. The geometry of the described arrangement is then such that the pivot pin 120 and the lever assembly 94 centrally mounted thereon are centered between the shafts 42 and 30. In addition, the cranks 90 and 92 are arranged so that the first connecting pins 102 and 104 are the same radial distance from their respective shafts 42 and 30 and are displaced therefrom in opposite directions, the same being true of the second connecting pins 110 and 111. In the position illustrated in FIGS. 2 and 5, for example, the first connecting pins 102 and 104 are displaced to the left and right respectively, and the second connecting pins 110 and 111 are displaced respectively downwardly and upwardly, from the respective shafts 42 and 30. Consequently, the lengths of the arms of the first lever 106 measured from the respective first connecting pins 102 and 104 to the centrally positioned pivot pin 120 are equal, the same being true of the second lever 107 and the second connecting pins 110 and 111 in engagement therewith.

With the described arrangement, rotation of the driving crank 90 causes the connecting pins 102 and 110 thereof to rotate the levers 106 and 107 about the pivot pin 120, which in turn drives the connecting pins 104 and 111 of the driven crank 92 to produce an identical rotation thereof. This may be appreciated by a comparison of the operating position illustrated in FIGS. 2 and 5, in which the carriage 14 is at the left hand limit of its reciprocation and the cam follower pin 46 is consequently to the left of the peak 48a of cam track 48, with the op-

erating position of FIGS. 1 and 3 in which the carriage has been traversed to the right hand limit of its reciprocation and the cam follower pin has traversed the peak of the cam track from left to right to turn the driving crank 90 over in a counterclockwise direction. It is seen that such motion results in driving the lever assembly 94 so that the driven crank 92 is also turned over in a counterclockwise direction for rotating the spreader box shaft 30 and thus reverse the spreader box 28. An oppositely directed traverse of the carriage 14 causes 10 clockwise rotation of the cranks 90 and 92.

As the driving crank 90 turns from the position of FIGS. 2 and 5, the connecting pin 102 will move substantially perpendicularly to the longitudinal axis of lever 106, thus rotating that lever clockwise about pivot 120 15 and thereby causing a similar movement of the connecting pin 104 perpendicularly to the longitudinal axis of the lever 106. The translational movements of the opposite ends of lever 106 are in opposite directions, i.e. up at the left and down at the right, because the rotary motion 20 of the lever is about the centrally located pivot. But this is canceled by the fact that the driving crank connecting pin 102 and the driven crank connecting pin 104 are on opposite sides of their respective axes of rotation, the shafts 42 and 30. This results in rotation of 25 the driven crank 92 in the same angular sense as that of the driving crank 90, i.e. counterclockwise in the example given. The fact that the opposite arms of the levers 106 are equal assures the transfer of motion from the driving crank connecting pin 102 to the driven crank 30 connecting pin 104 in a 1:1 relationship.

When the connecting pins 102 and 104 are moving perpendicularly to the longitudinal axis of the lever 106, they are then in maximum motion-transferring relationship thereto. After the cranks 90 and 92 have 35 completed approximately one quarter of a revolution, with still about another quarter of a revolution to go for reversing the spreader box 28, the connecting pins 102 and 104 are then in a dead center position wherein they move longitudinally of the lever 106. When this stage 40 is reached, the rotation of the cranks 90 and 92 moves the respective connecting pins 102 and 104 thereof along the length of the respective longitudinal slots 106a and 106b instead of against the walls thereof, and therefore the connecting pins then transfer substantially no motion to and from the lever 106. As a result, the driving crank connecting pin 102 must be turned past this dead center position before it will again begin to drive the lever 106, and when it does so, having traveled over center, it will thenceforth rotate the lever in the counterclockwise direction, i.e. opposite to its direction of rotation before traveling over center. The driven crank connecting pin 104, which is in a position similar to that of the driving crank connecting pin 102, reaches its dead-center position simultaneously therewith, after which no motion is transferred from lever 106 to the driven crank connecting pin 104 and the driven crank 92 becomes temporarily stalled at dead center. This raises the possibility that when the lever 106 begins to rotate in the opposite angular direction such motion might then cause the driven crank 92 to rotate in the wrong, i.e. the clockwise direction during the ensuing quarter turn, thus sending the driven crank back to its original position instead of completing the necessary half turn to reverse the spreader box 28.

It is for this reason that the second lever 107 and second connecting pins 110 and 111 are provided. These members exactly duplicate the driving relationship of the first lever 106 and connecting pins 102 and 104, by virtue of their identical construction and arrangement. The second connecting pins 110 and 111, however, are angularly displaced about the respective shafts 42 and 30 from the respective first connecting pins 102 and 104 of the same crank 90 or 92, this being achieved by securing the first and second crank arms 98, 108 and 100, 109 of each

crank 90 and 92 to the respective first connecting pins 102 and 104 thereof at an angle to each other. Consequently, the first set of connecting pins 102 and 104 and the second set of connecting pins 110 and 111 reach any given operating stage, and in particular the dead center stage, at different phases of the rotations of the cranks 90 and 92. The optimum angular displacement between them is the one which places the first connecting pins 102 and 104 in maximum motion-transferring relationship to the first lever 106 when the second connecting pins 110 and 111 are in minimum motion-transferring relationship to the second lever 107, and vice-versa. It is apparent from the geometry of the structure that this angle is equal to the arccosine of: the distance from the axis of a shaft, e.g. shaft 42, to the axis of an associated connecting pin, e.g. pin 110, divided by the distance from the axis of that shaft to the axis of the central pivot pin 120. With any angular displacement between the sets of connecting pins, however, whether it is the optimum one or not, at all stages of the rotation of the driving crank 90 at least one set of connecting pins will be in a position other than dead center so as to keep the driven crank 92 rotating in the same angular direction and thereby preclude any possibility of a reversal owing to the ambiguity of a dead center position of the other set of connecting pins.

As best seen by comparing the solid and broken-line views of FIG. 3, the slidable nature of the connection between the lever assembly 94 and the cranks 90 and 92 and the action of the diamond linkage 112-115 cooperate to preserve the driving relationship between the cranks and the lever assembly as the driven crank 92 rises during elevation of the block 32, spreader box shaft 30, and spreader box 28 by the drive chain 34 and sprockets 36. As driven crank 92 rises, the distance between that crank and the driving crank 90 increases. This is compensated for by sliding of the connecting pins 102, 104, 110, and 111 outwardly from the central pivot pin 120 longitudinally along the respective slots 106a, 106b, 107a, and 107b of the lever assembly 94.

The upward motion of spreader box shaft 30 raises the right hand linkage bar 113 pivotally connected thereto, which has the effect of rotating the entire pantograph linkage 96 upwardly about the drive shaft 42 to which the left hand linkage bar 112 is pivotally connected and opening up the linkage to make the diamond-shaped structure 112-115 wider and shallower as indicated by the broken-line view of FIG. 3. This raises the lower pivot pin 120 on which the lever assembly 94 is carried, thus rotating the lever assembly so that the right hand end thereof moves upwardly along with the driven crank 92, the lever arms 106 and 107 rotating counterclockwise about their respective driving crank connecting pins 102 and 104.

As the shape of the diamond linkage 112-115 changes 55 the equality of length between the upper bars 112 and 113, between their extensions 112a and 113a, and between the lower bars 114 and 115 assures that the lower pivot pin 120, carrying the lever assembly 94, floats with the pantograph linkage 96 in response to motion of the shaft 30 in such a way as to remain always centered along the line between the two shafts, 42 and 30.

Then the fact that the connecting pins of each set 102 and 104 or 110 and 111 are positioned in matched relationship to their respective shafts 42 and 30 as previously described assures that the lengths of the arms 65 of the lever assembly 94 measured from the pivot pin 120 to the respective connecting pins of each set will remain equal although increasing as the connecting pins slide outwardly along the longitudinal slots 106a, 106b, 107a, and 107b. This preserves the 1:1 correspondence between the motions of the driving crank connecting pins 102, 104 and the driven crank connecting pins 110, 111 respectively as the driven crank 92 is elevated.

It will therefore be appreciated that a reversing coupling in accordance with this invention is simply and

sturdily constructed, and functions in such a manner that minor inaccuracies in manufacture or assembly are not critical, while nevertheless meeting the operating requirements of continuous transmission of rotary motion between shafts separated by a varying distance.

While preferred embodiments of the invention have been shown and described herein, it is obvious that numerous additions, changes and omissions may be made therein without departing from the spirit and scope of the invention.

What we claim is:

1. In a machine for spreading cloth in superposed layers including a carriage reciprocable between limits and a device for spreading said cloth fixed on a first shaft mounted for rotation on said carriage to turn said cloth-spreading device about at the limits of reciprocation thereof and for movement on said carriage to raise said cloth-spreading device as the height of said superposed layers increases; a mechanism for turning said cloth-spreading device in different vertical positions thereof comprising a driving crank, a second shaft rotatably mounting said driving crank at a fixed location on said carriage, means for rotating said second shaft for turning said driving crank over as said carriage reaches the limits of reciprocation thereof, a driven crank secured to said first shaft to turn said cloth-spreading device and to move vertically therewith, lever means formed with longitudinal slots at opposite ends thereof, both of said cranks including connecting pins projecting therefrom at locations radially offset from the respective centers of rotation thereof and engaging said respective longitudinal slots to make a rotary driving connection between said lever means and each of said cranks and permitting sliding motion of said lever means between said cranks to compensate for vertical movement of said driven crank, and a floating pivot mounting said lever means for pivotal movement whereby to transmit turning motion between said cranks and positioned for floating movement whereby to center said floating pivot between said first and second shafts in different vertical positions of said driven crank.

2. In a machine for spreading cloth in superposed layers including a carriage reciprocable between limits and a device for spreading said cloth fixed on a first shaft mounted for rotation on said carriage to turn said cloth-spreading device about at the limits of reciprocation thereof and for vertical movement on said carriage to raise said cloth-spreading device as the height of said superposed layers increases; a mechanism for turning said cloth-spreading device in different vertical positions thereof comprising a second shaft rotatably mounted at a fixed location on said carriage, a driving crank fixed to said second shaft, means rotating said second shaft for turning said driving crank over as said carriage reaches the limits of reciprocation thereof, a driven crank fixed to said first shaft to turn said cloth-spreading device and to move vertically therewith, lever means formed with longitudinal slots at opposite ends thereof, both of said cranks including connecting pins projecting therefrom at locations radially offset from the respective centers of rotation thereof and engaging said respective longitudinal slots of said lever means to make a rotary driving connection thereto, said connecting pins and said lever means being so arranged as to be in maximum motion-transferring relationship to each other at different phases of the rotation of said cranks, said connecting pins being sized to permit longitudinal sliding motion of said lever means between said cranks to compensate for vertical movement of said driven crank, a pantograph linkage connected between said first and second shafts, and a floating pivot mounting said lever means on said pantograph linkage for pivotal movement whereby to transmit turning motion between said cranks and positioned for floating movement with said pantograph linkage whereby to center said floating pivot between said first and second shafts in different vertical positions of said driven crank.

3. A mechanism according to claim 2 wherein said respective cranks include respective first crank arms fixed to said respective shafts, respective first connecting pins projecting from said respective first crank arms, respective second crank arms fixed to said respective first connecting pins, and respective second connecting pins projecting from said respective second crank arms, said lever means including a first lever having respective longitudinal slots at opposite ends thereof receiving said respective first connecting pins, and a second lever having respective longitudinal slots at opposite ends thereof receiving said respective second connecting pins, said first and second connecting pins of each crank being angularly offset from each other so as to be in maximum motion-transferring relationship to said respective levers at different phases of the rotation of said cranks.

4. In a cloth-spreading machine of the type wherein cloth is spread in superposed and folded layers by the movements of a reciprocating carriage and a rotating cloth-spreading device mounted on said carriage for vertical movement, actuating means for rotating said cloth-spreading device comprising a driving shaft rotatably mounted on said carriage at a fixed location, a driving crank secured thereto, a driven shaft operatively connected to said cloth-spreading device and movable vertically therewith, a driven crank secured thereto, means to rotate said driving shaft, and means for interconnecting said driving crank to said driven crank for transmitting rotating motion irrespective of the vertical position of said driven crank comprising a pair of crossed links pivotally interconnected intermediate their ends, a floating pivot mounting said pivotal interconnection intermediate said first and second shafts, and sliding connections including complementary pins and slots between said cranks and said crossed links.

5. In a machine for spreading cloth in superposed layers including a carriage mounted for reciprocal movement between limits and a device for spreading said cloth mounted on said carriage for turning movement at the limits of reciprocation of said carriage and for vertical movement on said carriage to raise said cloth-spreading device as the height of said superposed layers increases; a mechanism for turning said cloth-spreading device comprising a driving crank rotatably mounted at a fixed location on said carriage, means for rotating said crank as said carriage reaches the limits of its reciprocation, a driven crank operatively connected to said cloth-spreading device and mounted to move vertically therewith, a pair of levers pivotally interconnected intermediate their ends, means mounting said pivotal interconnection at a location equidistant from said driving crank and said driven crank, means slidably interconnecting said driving crank and said levers at one end thereof and said driven crank and said levers at the other end thereof providing a rotatable driving connection between said driving and driven crank, said slideable interconnecting means permitting longitudinal sliding motion between said cranks to compensate for vertical movement of said driven crank with said cloth-spreading device and to provide rotation of said driven crank at various vertical locations as a result of rotation of said driving crank.

6. In a machine for spreading cloth in superposed layers including a carriage mounted for reciprocal movement between limits and a device for spreading said cloth mounted on said carriage for turning movement at the limits of reciprocation of said carriage and for vertical movement on said carriage to raise said cloth-spreading device as the height of said superposed layers increases; a mechanism for turning said cloth-spreading device comprising a driving crank rotatably mounted at a fixed location on said carriage, means for rotating said crank as said carriage reaches the limits of its reciprocation, a driven crank operatively connected to said cloth-spreading device and mounted to move vertically therewith, a pair of levers pivotally interconnected intermediate their ends, means mounting said pivotal interconnection

tion at a location intermediate said driving crank and said driven crank, means slidably interconnecting said driving crank and said levers at one end thereof and said driven crank and said levers at the other end thereof providing a rotatable driving connection between said driving and driven crank, said slideable interconnecting means permitting longitudinal sliding motion between said cranks to compensate for vertical movement of said driven crank with said cloth-spreading device and to provide rotation of said driven crank at various vertical locations as a result of rotation of said driving crank.

7. In a machine for spreading cloth in superposed layers including a carriage reciprocably mounted for movement between limits and a device for spreading said cloth mounted on said carriage for turning movement at the limits of reciprocation of said carriage and for vertical movement on said carriage to raise said cloth-spreading device as the height of said superposed layers increases, a mechanism for turning said cloth-spreading device comprising a driving crank rotatably mounted at a first location on said carriage, means for rotating said crank as said carriage reaches the limits of its reciprocation, a driven crank operatively connected to said cloth-
